* cited by examiner

Primary Examiner — David Muller(74) *Attorney, Agent, or Firm* — Joseph T. Leone, Esq.; DeWitt Ross & Stevens S.C.(57) **CLAIM**

The ornamental design for a biological fluid container nozzle, as shown and described.

DESCRIPTION

FIG. 1 is a front elevation view of a biological fluid container nozzle showing my new design;

FIG. 2 is a rear elevation view thereof;

FIG. 3 is a left elevation view thereof;

FIG. 4 is a right elevation view thereof;

FIG. 5 is a bottom plan view thereof; and,

FIG. 6 is a top plan view thereof.

The broken lines shown in the drawings are for illustrative purposes only and form no part of the claimed design.
